UNITED STATES PATENT OFFICE.

HORACE CLIFFORD BROTHERS, OF WORCESTER, MASSACHUSETTS, ASSIGNOR, BY MESNE ASSIGNMENTS, TO FRANK R. BATCHELDER, OF WORCESTER, MASSACHUSETTS.

WOVEN CARRIER.

1,344,377.

Specification of Letters Patent. Patented June 22, 1920.

Application filed August 13, 1918. Serial No. 249,715.

To all whom it may concern:

Be it known that I, HORACE C. BROTHERS, a citizen of the United States, residing at Worcester, in the county of Worcester, State 5 of Massachusetts, have invented a certain new and useful Improvement in Woven Carriers, of which the following is a specification, reference being had therein to the accompanying drawings.

10 The invention has relation to pocketed carriers made of woven material, namely carriers on the order of those which are used for holding and carrying cartridges, packaged first-aid supplies, etc. It consists 15 in a woven carrier having one or more tilt-able pockets and containing the novel features of construction to which reference is made hereinafter.

Figure 1 of the drawings is an isometric 20 view of a portion, including two pockets, of a cartridge-carrier embodying the invention.

Fig. 2 is a view in section along the line 2—2 of Fig. 1, and Fig. 3 is a view in section along the line 3—3 in Fig. 1.

25 Having reference to the drawings,—

The carrier-construction shown therein comprises a body or band 1, tilttable pockets 2, 2, and covers or flaps 3, 3, for the said pockets. The hinge-connections, described 30 hereinafter, of the pockets at their bottoms with the body or band enables the pockets to occupy either a vertical position against the body or band, as in Fig. 3 and at the left in Fig. 1, or an outwardly-inclined position 35 as in Fig. 2 and at the right in Fig. 1, the extent of the outward movement of the pockets being limited by means of check-bands 4, each having one end thereof attached to the body or band 1 and the other 40 end thereof attached to the back of one of the pockets. The outwardly-inclined position of the pockets facilitates the insertion of cartridges or other contemplated articles into the pockets, and the withdrawal of the 45 contents of the pockets.

The cover or flap 3 for each pocket is attached by one end thereof to the body or band 1, as heretofore. As shown, such end is inserted into a housing-slit 5 that is 50 formed in the upper margin of the said body or band in the process of weaving the latter, and is made fast therein by securing the two sides of said housing-slit and the

inserted end together by a line 6 of fastenings, preferably stitches. When the pocket 55 occupies its normal position, that is to say its vertical position against the body or band 1, shown in Fig. 3 and at the left in Fig. 1, the cover may be folded forward over the open top of the pocket and down in 60 front of the latter. Fastener-members 7, 8, of the usual glove-fastener (or so-called ball-and-socket) type are shown applied to the pocket-front and the free end of the 65 cover or flap. When the two members of the fastener are interengaged as in Fig. 3 and at the left in Fig. 1, the cover thereby is fastened down over the pocket and the 70 pocket itself is fastened back in its normal position. Upon disengagement of the two 75 fastener-members, the pocket will be free to fall outward into the inclined position that is represented in Fig. 2 and at the right in Fig. 1. Other known fastener-devices may be substituted in practice.

The hinging of the pockets to the body or band 1 is provided for by weaving the pockets with a projecting fin 9, Figs. 2 and 3, along the bottom of each, and weaving the lower margin of the body or band with 80 a housing-slit 10. The said fin is inserted into the said housing-slit, and is secured therein by a line 11 of fastenings, preferably 85 stitches.

In making the pockets, a series of pockets 85 is woven in the length of a continuous web. The open mouths of the pockets are located at one margin of the web, so that the returns of the successive picks of weft around the marginal warp-threads of the different 90 plies constituting the back and body of a pocket produces finished selvage-edges at the mouth of the pocket. The web is woven with a continuous flange or fin along the other margin thereof, projecting beyond the 95 pocket-bottom. When the web is cut up into pocket-units by cutting across it between the successive pockets, the portion of this flange or fin that remains attached to each pocket constitutes the hinging fin 9. The web also 100 is woven with the pockets spaced at such distances apart that when the portions of web connecting the pockets together are cut through between one pocket and the next, projecting side-margins 12, 12, are left upon 105 the lateral portions of the pockets. These

are then turned in against the pocket-backs, as shown, and secured in place by stitches 13, Fig. 1, thereby completing the pockets in readiness for attachment to the body or band 1.

What is claimed as the invention is,—

- 10 1. A carrier formed of woven material, comprising a back formed with a housing-slit in its lower portion, a woven pocket having at its bottom a projecting fin that is entered into said housing-slit and secured therein, forming a hinge-connection, and means for limiting the forward swing of the pocket away from the back.
- 15 2. A carrier formed of woven material, comprising a back formed with a housing-slit in its lower portion, a woven pocket having at its bottom a projecting fin that is entered into said housing-slit and secured therein, forming a hinge-connection, means for limiting the forward swing of the pocket away from the back, and a pocket-cover or flap that is attached to the back and adapted

to fasten the pocket in normal position close to the back.

25

3. A carrier formed of woven material, comprising a back formed with a housing-slit in its lower portion, a woven pocket having a selvaged mouth at its top, projecting side-margins that are turned and fastened against the back of the pocket, and a projecting fin at its bottom that is entered into said housing-slit and secured therein, forming a hinge-connection, means for limiting the forward swing of the pocket away 30 from the back, and a pocket-cover or flap that is attached to the back and adapted to fasten the pocket in normal position close to the back.

35 In testimony whereof I affix my signature 40 in presence of two witnesses.

HORACE CLIFFORD BROTHERS.
